C. A. ROLFE

GOLF TEE

Filed Jan. 19, 1922

Inventor:
Charles A. Rolfe
By *James T. Parker*,
his Attorney

UNITED STATES PATENT OFFICE.

CHARLES A. ROLFE, OF REDLANDS, CALIFORNIA.

GOLF TEE.

Application filed January 19, 1922. Serial No. 530,320.

To all whom it may concern:

Be it known that I, CHARLES A. ROLFE, a citizen of the United States, residing at Redlands, in the county of San Bernardino and State of California, have invented new and useful Improvements in Golf Tees, of which the following is a specification.

This invention has to do with a tee for supporting a golf ball, or the like, and it is 10 an object of the invention to provide a tee which is simple, effective, and convenient.

It is an object of this invention to provide a tee for holding a ball, or the like, to take the place of the dirt tee heretofore commonly used, and which is more convenient to carry and handle, generally, than the tees heretofore made and proposed to take the place of the dirt tee. The present tee is adapted to be made of paper, or the like, 20 and is as simple and convenient to carry as an ordinary sheet of paper.

A distinctive feature of the invention is the provision of a paper tee which folds flat so that it can be very easily and conveniently handled and carried and which opens out to form a particularly effective support. The tee in folding flat is very easily packed and handled and is therefore particularly convenient and desirable for use.

Another noteworthy feature of the invention is the provision of a series or group of tees which forms a sheet such as can be bound into a book, or the like. The several tees of a group can be formed from a single 35 piece of paper, or the like, so that they remain connected until they are used. The group of tees can be bound into a book or pamphlet, say, for instance, a book of tees or a score book, and can be removed or detached one by one as they are required for use.

Another noteworthy feature of the invention is the manner in which the tees are formed so that they readily open out after 45 having been folded. The tees readily open out so that they will stand firmly and form effective supports.

The various objects and features of the invention will be best and more fully understood from the following detailed description of a typical preferred embodiment of the invention throughout which reference is had to the accompanying drawings in which:

Fig. 1 is a perspective view of a score

book showing series or groups of tees provided by the present invention bound with the leaves of the book; Fig. 2 is a view showing a series or group of tees similar to those shown bound into the book in Fig. 1; 60 Fig. 3 is a plan or end view of one of the tees in its opened out or operating condition; Fig. 4 is a plan or end view of a tee in a collapsed or folded condition; and Fig. 5 is a view showing a tee provided by the 65 present invention supporting a ball; the tee being shown in sections.

The tee 10 provided by the present invention is a tube of paper, or the like, sufficiently long to support a ball the desired distance 70 above the ground and sufficiently large or wide across to securely or effectively support the ball. In accordance with the invention the tee has longitudinal folds or creases 11 and 12 which allow it to be folded flat as 75 illustrated in Figs. 1 and 4 and to be opened out so that it is substantially square in cross sectional configuration as illustrated in Figs. 3 and 5. In the particular form of the invention illustrated in the drawings the 80 two creases 11 are at the edges of the sheet or strip formed when the tee is folded while the creases 12 are at the middle of the strip, as clearly illustrated in Fig. 4. It is preferred, although not necessary in accordance 85 with the broader aspect of the present invention that the creases 11 be 180° apart around the tee, and that the creases 12 be half way between the creases 11 so that they also are 180° apart around the tee. This 90 arrangement and spacing of the creases causes the tee to take the form of a square when opened out, as illustrated in Fig. 3. It will be obvious how, in accordance with the broader aspects of the present invention, 95 the tee might be provided with a greater or less number of creases than I have herein specified so that it will fold somewhat differently than I have herein set forth and will be somewhat different in shape when 100 opened out than the particular tee herein set forth. In practice it is ordinarily desirable that the tee have only four folds, the two folds 11 and the two folds 12, and that the folds be arranged and spaced substantially 105 as I have herein set forth. In accordance with the preferred form of the invention the folds 11 are distinctly formed in the tee when it is manufactured so that the tee always thereafter has more or less tendency 110

to open out from the folded condition illustrated in Fig. 4 and therefore is readily opened when required for use.

In accordance with the invention the tees 5 10 may be formed in series or groups by taking a comparatively long tube A of the proper size and dividing or laying it out into a plurality of parts by heavily stamped lines or rows of perforations 13. The rows 10 15 13 of perforations are transverse of the tube A and divide it into a plurality of tees 10 which can be readily detached or separated by tearing along the rows of perforations. In the tube A shown bound into the book 15 20 in Fig. 1 the rows of perforations are evenly spaced and are so spaced that the tube is divided into a plurality of tees 10 of average height. In the tube A illustrated in Fig. 2 there are two spaced rows 20 25 of perforations at the points of division of the tees so that tees of different heights can be had by tearing along the different rows of perforations. It will be obvious how tees of various sizes may be had with a suitable number arrangement or spacing of rows of perforations. When a tee has been torn from the series or group it can be easily opened up to the condition illustrated in Figs. 3 and 5. In practice it is particularly desirable that the divisions between the tees in the series be made by rows of perforations as this means of dividing the several tees leaves their edges more or less rough or ragged so that they will not readily slide on the ground.

From inspection of Figs. 1 and 2 of the drawings it will be obvious how series of tees of suitable length may be made and how the series may be easily and conveniently bound into a book or pamphlet. In Fig. 1 I show several series of tees bound between the leaves 15 of a score book. This is a particularly convenient arrangement as the tees are incorporated in the score book so

that they do not inconvenience the player 45 in any way.

Although I hereinabove refer to the tees provided by the present invention as being formed of paper it is to be understood that I do not specifically limit myself to the use of paper as it is obvious that other similar materials might be advantageously used. Further, the tubes A which are divided for the purpose of forming several tees, and in fact the tees themselves, may be seamless tubes of paper, or the like, or may be sheets of paper with their edges lapped or otherwise suitably connected to form tubes.

From the foregoing description and from inspection of the drawings it will be obvious that the tee provided by the present invention is extremely simple, inexpensive, effective, and particularly convenient and desirable for use.

Having described only a typical embodiment of my invention I do not wish to limit myself to the particular details hereinabove set forth but wish to reserve to myself any changes or variations that may appear to those skilled in the art or which may fall within the scope of the following claim.

Having described a preferred embodiment of my invention, I claim:

A ball tee, embodying a flattened paper tube with creases at the folded edges of the flattened tube, and other creases intermediate the edge creases, said last mentioned creases tending to cause the flattened tube to open outwardly into a substantially square formation.

In witness that I claim the foregoing I have hereunto subscribed my name this 7th day of January 1922.

CHARLES A. ROLFE.
